UNITED STATES PATENT OFFICE.

EMERICK HODALY, OF ARKANSAS CITY, KANSAS.

SUSPENDERS.

Application filed January 22, 1924. Serial No. 687,814.

To all whom it may concern:

Be it known that I, EMERICK HODALY, a citizen of the United States, residing at Arkansas City, in the county of Cowley, State of Kansas, have invented certain new and useful Improvements in Suspenders, of which the following is a specification.

This invention relates generally to improvements in suspenders, more particularly to fastening means carried by suspenders whereby the length of the suspenders may be adjusted, and it consists in the combinations, constructions, and arrangements herein described and claimed.

15 An object of the invention is to provide suspenders having novel fastening means for adjusting the length of the suspender straps without positioning any part of the fastening means against an underlying garment.

A further object of the invention is to provide suspenders having co-operative fastening elements carried by the body and an end portion of each suspender strap, the co-operative fastening elements being adapted to engage each other to hold the strap securely although releasably in adjusted position.

A further object of the invention is to provide suspenders having co-operative fastening elements carried by the body and an end portion of each suspender strap for engaging each other to adjust the length of the strap, the co-operative fastening elements having no sharp corners or projections likely to injure an underlying fabric and being adapted to be engaged with or disengaged from each other quickly and easily.

Other objects and advantages will be apparent from the following description, considered in conjunction with the accompanying drawings, in which:

Figure 1 is a perspective view showing suspenders embodying the invention in position to support over-all.

Figure 2 is a fragmentary perspective view of one of the straps of the suspenders, illustrating particularly the means whereby the strap may be adjusted in length,

50 Figure 3 is an edge view showing a portion of the suspender strap engaged with a garment, only a portion of the latter being shown, and

55 Figure 4 is a fragmentary perspective view showing the parts exhibited in Figure

2 with the co-operative attaching elements carried by the strap disengaged.

Referring now to the drawings, the suspender straps are designated 1. Each strap preferably decreases gradually in width toward one end thereof as clearly shown in the drawings, and is provided at the said end with a loop 2.

A relatively narrow strip 3 of a flexible material, such as a suitable fabric is placed upon the outer face of each strap 1, the strip 3 extending longitudinally of the strap with the lateral edges thereof spaced from the corresponding edge of the strap. The strip 3 is secured to the strap 1 by spaced-apart rows of stitching 4 which extend transversely of the strap, whereby the portion of the strip extending between each two adjacent rows of stitching 4 constitutes a half loop 5 and a series of such half loops 75 extending longitudinally of the strap adjacent to the said one end of the latter thus is provided.

A fastening member, designated generally 6, is carried by the strap at its said one end 80 for engaging with any one of the half loops 5, whereby the effective length of the strap may be varied. The fastening member 6 comprises two complementary substantially U-shaped sections 7 and 8, respectively, each 85 of which is formed of a length of wire or like material. The section 7 has the ends thereof fashioned to provide eyes, indicated at 9. The section 8 is fashioned at one of its ends thereof to provide an eye 10 which is engaged with one of the eyes 9 of the section 7, whereby the sections 7 and 8 will be 90 swingingly connected. The section 8 is provided at its other end with a hook 11 for engaging with the second eye 9 of the section 7. The web portion of the section 7 extends 95 through the loop 2. The section 8 is adapted to be inserted in any one of the half loops 5 at one end of such half loop and then extended through the half loop until the web 100 portion of the section 8 is disposed in the half loop and the ends of the section 8 are disposed at opposite ends of the half loop. It will be manifest that the fastening member 6 and therefore the loop 2 will be attached to the particular half loop 5 through which the section 8 extends when the hook 11 at the free end of the section 8 is engaged with the eye 9 at the free end of the section 7. The effective length of the strap thus 110

may be adjusted at will by placing the attaching member 6 in engagement with the respective half loops 5, selectively. The portion of the strap on which the strip 3 is disposed provides a backing for the half loops and prevents contact of the fastening member 6 with any garment which underlies the strap.

Each strap 1 may be provided with an attaching link or ring, such as that indicated at 12, the attaching link being arranged to slide on the portion of the strap between the proximate half loop 5 and the loop 2 and being adapted to engage with a button 13 carried by a garment 14.

The garment 14 may be over-all as illustrated in Figure 1, and the said one end of each of the straps 1 may be connected by means of the link 12 with the bib or front 20 portion of the over-all, the straps 1 being provided at their other ends with any suitable means whereby they may be attached to the back portion of the garment or being permanently attached to the back portion of 25 the garment by stitching, as is usual.

From the foregoing description of the various parts of the device, the operation thereof may be readily understood. A suspender strap equipped with fastening means embodying the invention and as described in the foregoing, can be adjusted to vary the effective length thereof quickly and easily, has a neat appearance, and will not cause injury to any underlying garment. Moreover, any adjustment of the strap possible because of the operation of the fastening means will be maintained until a further adjustment of the strap has been made as the

co-operative fastening members will not accidentally disengage each other.

Obviously, my invention is susceptible of embodiment in forms other than that illustrated in the accompanying drawings, and I, therefore, consider as my own, all modifications and adaptations of the form of the device disclosed herein which fairly fall within the scope of the appended claim.

I claim:

In a garment supporting device, a strap having a loop at one end thereof and having a series of half loops provided on the outer face thereof, said series of half loops extending longitudinally of said strap and terminating at one end adjacent to said one end of the strap, a link slidable on the strap between said series of half loops and the said one end of the strap, a fastening member for securing said loop to any one of said half loops, said last-named fastening member comprising two substantially U-shaped complementary sections each formed of a single length of wire, each section being hingedly attached at one end to the corresponding end of the other section, and one of said sections being provided at its second end with an eye portion and the second section being provided at its second end with a hook engageable with said eye portion, one of said sections having the web portion thereof disposed in said loop and the other of said sections being adapted to be extended through any one of said half loops before being placed in engagement at its upper end with the free end of the first section.

EMERICK HODALY.
